UNITED STATES PATENT OFFICE.

JOHN F. O'CONNOR, OF EASTON, PENNSYLVANIA, ASSIGNOR OF ONE-HALF
TO FRANK W. COOLBAUGH, OF EASTON, PENNSYLVANIA.

RAILWAY-CAR TRUCK.

SPECIFICATION forming part of Letters Patent No. 717,603, dated January 6, 1903.

Application filed April 23, 1902. Serial No. 104,240. (No model.)

To all whom it may concern:

Be it known that I, JOHN F. O'CONNOR, a citizen of the United States, residing at Easton, county of Northampton, State of Pennsylvania, have invented certain new and useful Improvements in Railway-Car Trucks, of which the following is a specification.

This invention relates to improvements in that class of railway-car trucks which are provided with a pivoted jaw which can be swung outward and upward for the purpose of removing the journal-box horizontally from the truck in the direction of the rails through the opening formed by swinging upward said jaw.

The objects of my invention are to simplify the construction of the parts of the truck, to strengthen the same, and to give the truck greater clearance between its lowest parts and the rail, and also to give the lower corners a finish, so that they will not be apt to catch on the road-bed, cross-rods, switch-rods, &c., in case of derailment.

In the accompanying drawings, in which like letters of reference indicate like parts in all the figures, Figure 1 is a side elevation of my improved truck, parts being in section and others omitted. Fig. 2 is a plan view of the reinforcing-casting, parts of the hinged jaw being in section. Fig. 3 is a vertical transverse sectional view showing the hinged jaw. Fig. 4 is a side view of the hinged jaw. Fig. 5 is a horizontal sectional view on the line 5-5 of Fig. 4.

The sides of the truck are formed of I-beams A, which are split and spread upward and downward at their ends, so as to form an opening for receiving the springs and journal-box, as shown on the left-hand end of Fig. 1.

On the outer surface of each I-beam A and at each end thereof a U-shaped malleable-iron casting or reinforcing-frame B is riveted, the inner leg B' of which is longer than the outer leg B², and said inner leg extends from the upper surface of the bottom flange of the I-beam A, at the split and spread end thereof, to the under surface of the top flange. This casting B has a flange b along its inner edge, and at the top this flange is widened out to form a circular seat C for the upper end of

the bearing-spring C', said seat having a recess for receiving the upper end of the spring. On each face of the casting B a curved wing D extends from diametrically opposite points 55 of said circular seat C downward and inward at an angle of about forty-five degrees at the flange b for the purpose of strengthening and reinforcing the upper inner corner of the casting, which corner is subjected to great 60 strain. The wings D connect at their upper ends with the circular spring-seat on a transverse or diametrical line through said spring-seat, locked midway between the front and rear legs of said U-shaped frame. 65

A latch E is pivoted at its upper end to the shorter outer leg B² of the U-shaped casting B by a bolt V and is provided on its inner edge with a flange of the same size as the flange b on the longer leg B'. At its outer 70 edge the latch E is provided with a narrower flange e' on each side. The flange e' of the latch is gradually widened out at a point a short distance above its lower end and is curved downward and inward to form a runner F, 75 the lower inner end of which terminates in an arm G, which seats against the under side of the flange a' of the split and spread I-beam. Above this flange part of the web remains, forming a ridge a², at the outer end of which 80 a portion of the web forms a spur a³, projecting slightly above the flange a² and having its upper edge inclined downward and outward. The latch E is provided at the bottom 85 of its inner edge and directly above the arm G with a socket E' for receiving the flange a' and with a recess E² for receiving the spur a³. At each side of this recess E² a bolt-socket E³ is formed, the outer face of which is flush with the inner flange of the latch, and 90 each bolt-socket is provided with a hole through which a bolt can be passed. At the free end of the arm G on the latch E a recess H, open at the bottom, is formed at each side of the longitudinal central web, and in the 95 top of said recess a bolt-hole is formed, through which a bolt can be passed.

On the upper surface of the bottom flange a' of the split end of the I-beam a casting L is secured, which has a longitudinal hollow 100 central ridge for receiving the ridge a² on the flange a', and this casting has two laterally-

extending wings J, which rest upon the upper surface of the bottom flange a' . Two rivets J' are passed through said wings J of the casting and through the bottom flange of the 5 split end of the I-beam, and in advance of each rivet a bolt-hole is formed in each wing J, through which a bolt M can be passed, which bolt also passes through the corresponding hole in the recess H of the arm G 10 on the latch E when said latch is in a closed position. At the outer end of said casting J a transverse wall J² is formed in line with the rear end of the spur a^3 , which wall has a bolt-hole at each side of the hollow ridge that receives the ridge a^3 . When the journal-box 15 has been placed into the proper opening in the truck, the latch E is swung down, its arm G resting against the under side of the flange a' and the lower part of the inner flange e of 20 said latch resting against the transverse end wall J² of the casting J. Two bolts S are then passed through the corresponding holes in the bolt-sockets E³ on the latch. Nuts are screwed on the outer ends of these bolts. 25 Two bolts M are passed through the holes in the wings of the casting J and through the corresponding holes in the arm G of the latch E, and on the lower projecting ends of these bolts nuts are screwed. A bolt T is then 30 passed through corresponding holes in the forked upper hinged end of the latch and in the short leg B² of the casting B and in the split end of the beam and a nut screwed on said bolt.

35 It will be observed that the lower ends of the bolts M are contained within the recess H, formed at the inner end and under side of the arm at the bottom of the latch and do not project sufficiently to catch on anything and can 40 ride over sleepers, switch-rods, &c., in case of derailment without catching on them. In case of a derailment, the rounded and wide shoe F behind the outer ends of the bolts S and the nuts thereon are concealed, and can run 45 and slide over sleepers, ties, and switch-rods, and the like without digging into them or catching on them. This shoe or runner not only protects the truck from damage in case of derailment, but also prevents the truck 50 from catching on the track and causing a pile-up.

Having described my invention, what I claim as new, and desire to secure by Letters Patent, is—

55 1. In a railway-car truck, the combination with side beams having opened ends, of a U-shaped casting secured on each opened end, a latch hinged to each casting, a spring-seat formed on said casting, and wings extending 60 from the spring-seat to the casting, substantially as set forth.

2. In a railway-car truck, the combination with a side beam, having its ends opened, of a U-shaped casting secured on each opened 65 end, a latch hinged to each casting, a circular spring-seat formed on the casting and curved inclined wings extending from oppo-

site sides of the spring-seat to the casting at the upper inner corner of the same, substantially as set forth. 70

3. A railway-car truck having the lower outer corners of its side frame rounded and widened, substantially as set forth.

4. The combination with a railway-car truck, of hinged latches on the ends of the 75 same, and widened runners formed on the lower end of said latches, substantially as set forth.

5. In a railway-car truck, the combination with side beams, of latches pivoted at the ends 80 of the same, and extending below the bottom edges of said beams, and having their lower outer corners widened and rounded to form runners, substantially as set forth.

6. In a railway-car truck, the combination 85 with side beams, of latches pivoted on the sides of the same, and extending below the bottom edges of said beams, and having their lower outer corners rounded to form runners, and horizontal and vertical bolts for connecting the swinging end of the latch with the bottom of the said beam, substantially as set forth. 90

7. In a railway-car truck, the combination 95 with a side beam, having each end opened, of a U-shaped casting attached to each open end of the beam, a latch pivoted to each casting and provided at its swinging end with an arm fitting on the under side of bottom flange of the beam, substantially as set forth. 100

8. In a railway-car truck, the combination with a side beam, having its ends opened, of a U-shaped casting secured on each open end of the beam, a latch pivoted to the U-shaped casting and provided at its lower end with an arm fitting on the under side of the bottom flange of the beam, the outer face of said arm and lower part of the latch being rounded to form a runner, substantially as set forth. 105

9. In a railway-car truck, the combination 110 with a side beam, having its ends opened, of a U-shaped casting secured on the side of the beam at each open end, a latch pivoted to each U-shaped casting and provided at its lower end with an arm fitting on the under side of the beam and also provided above said arm with two bolt-sockets, substantially as set forth. 115

10. In a railway-car truck, the combination 120 with a side beam, having its ends opened, of a U-shaped casting secured on the side of the beam at each open end, a latch pivoted to each U-shaped casting and provided at its lower end with an arm and above the arm with bolt-sockets, a casting secured on the upper surface of the bottom part of the beam, and having a transverse end wall against which the bolt-sockets on the latch rest when the latter is in a closed position, substantially 125 as set forth.

11. In a railway-car truck, the combination with a side beam, having its ends opened, of a U-shaped casting secured at the side of the beam at each opened end, a latch pivoted to 130

each U-shaped casting, an arm on the lower end of said latch, which arm is provided at its free end and on its under side with recesses, substantially as set forth.

5 12. In a railway-car truck, the combination with a side beam, having openings formed in its ends, of a casting secured on the upper surface of the bottom part of said beam and provided with a transverse end wall having 10 bolt-holes, said end wall being a short distance back from the free end of the bottom part of the beam, a U-shaped casting secured on the open end of the beam, a latch secured to said casting and provided with bolt-sockets

and below said sockets with a recess for receiving that part of the bottom of the beam extending beyond the transverse wall of the casting on said bottom part of the beam, substantially as set forth.

In testimony whereof I have signed my name to this specification, in the presence of two subscribing witnesses, this 5th day of April, 1902.

JOHN F. O'CONNOR.
